UNITED STATES PATENT OFFICE.

ADELMER M. BATES, OF CHICAGO, ILLINOIS, ASSIGNOR TO BATES VALVE BAG COMPANY, OF CHICAGO, ILLINOIS, A CORPORATION OF WEST VIRGINIA.

CEMENT PACKER.

Application filed May 26, 1922. Serial No. 563,933.

To all whom it may concern:

Be it known that I, ADELMER M. BATES, a citizen of the United States, residing at Chicago, in the county of Cook and State 5 of Illinois, have invented a certain new and useful Improvement in Cement Packers, of which the following is a specification.

This invention relates to a bag or package filling machine wherein granular material is 10 forcibly fed into the package. It relates particularly to a feeding means.

My invention is illustrated more or less diagrammatically in the accompanying drawings, wherein:

15 Figure 1 is a fragmentary vertical cross section of the filling machine;

Figure 2 is a view on an enlarged scale of a portion of Figure 1 showing the discharge spout and control;

20 Figure 3 is an elevation with parts in section showing the opening and controlling slide;

Figure 4 is an elevation with parts in section of the impeller;

25 Figure 5 is a longitudinal section taken on line 5—5 of Figure 1 with parts omitted and showing the impeller in position;

Figure 6 is an elevation showing the discharge spout and controlling valve, with 30 parts in section.

Like parts are designated by like characters throughout.

A is the hopper to which the material is fed and from which it is downwardly 35 moved by the feeding wheel A' into a chest A² from which it falls into the impeller casing A³.

This casing is provided with a removable segment B, which forms about one-third of its bottom. This segment is bolted 40 onto the main casting which forms the remainder of the impeller casing. The particular form in which this is accomplished is shown in Figures 3 and 6. The casting B is provided with lateral extensions and

45 at its upper end there is a pair of enlarged perforations B' B' communicating with narrow slots B² B². The lower extension has a pair of slots B³ B³. The bolts or screws which hold the segment B in position are mounted in the main casting and

50 segment B is moved into position so that the heads of the bolts or screws pass through the enlarged holes B'. It is then slipped down so that the shank of the bolts or screws

55 move into the narrow slots. The screws are

then tightened and the segment is secured in position.

The segment B is perforated as at C and has fastened to it at this point a member C', which is provided with a perforation C² in continuation of the perforation C. Mounted so as to slide across the perforation C is a shutter C³, provided with a central perforation C⁴. This shutter is held in position by the member C' and may be moved 60 back and forth across the opening so as to control the discharge of material there-through. The member C' may be fastened to the segment B by bolts C⁵, shown in section in Fig. 3. A skirt portion C⁶ projects 65 downward from the outer end of the member C'.

D is a removable floor piece for the impeller casing. It is positioned at the point at which it has been determined the greatest 70 wear takes place, and it is made removable in order that replacement can be made. This member is perforated and is held in position by a bolt D' which passes through it and through a positioning finger D². The bolt 75 is sufficiently tightened to hold the parts in the position shown, and the set screw D³ in the outer end of the finger D² is manipulated further to tighten the bolt and to hold the parts more rigidly in position. This set 80 screw D³ also serves to adjust the segment B in position before the same is finally clamped by means of the bolts in slots B², B³.

E is a package holding frame pivoted at 85 E' upon a laterally extending rod E² which is itself pivoted at E³. The frame E is supported upon the ends of the scale beam E⁴, as at E⁵. The scale beam E⁴ is pivotally supported upon a knife edge E⁶. The bag or other package is supported in the frame E. The bag, which is preferably of the valve type, is provided with an opening in its top and is positioned so that the discharge spout F extends into the opening. As material is discharged into the bag which is supported upon the scale, the scale beam is gradually depressed. The nozzle F, since it is supported from the frame E, moves with the frame. The nozzle F is located 100 in a valve block F', and about this block F' and overlying the impeller casing is an apron F². The inner end of the nozzle tube F is chamfered so as to eliminate any possibility of the material being projected 105 110

against an abrupt edge whereby its discharge might be interfered with.

Supported together with the frame E are a pair of brackets G, which carry between them a locking lug G', notched on its lower end as at G². The upper end of this lug is split and is provided with a dog G³. The operation of this dog will not be described in detail as it forms no part of the present invention. It is sufficient to say that the member G' serves by means of its notched end G² to engage the fabric of the bag which is being filled and prevent accidental displacement of the same.

H is an impeller formed of a split hub each half of which is provided with two laterally extending arms H' H''. The impeller is mounted upon a driven shaft H² which is driven from any suitable source of power. The two parts of the impeller hub are fastened together by the screws H⁸ H⁹. To each of the arms H' is fastened a blade H⁴, which has a central corrugation H⁵ seated in a corresponding groove H⁷ in the arm H' of the hub. Thus each blade is prevented from twisting when the single bolt H⁸ which holds it in position is tightened, and its position in or out may readily be adjusted by the manipulation of this single bolt. The central corrugation H⁵ serves as a stiffening means as well as a positioning means for the blade. An elongated slot H⁶ is provided for the passage of H⁸, so that the blade may be adjusted in or out.

The impeller casing is provided with a lateral extension I, which adjoins a similar lateral extension I' from another impeller casing which forms part of the same machine. Since cement or other finely divided material is in the impeller casing it will circulate through the extension I, and in order to prevent its escape into the surrounding air or into the bearings of the machinery a readily applied flexible joint is used to connect the adjoining casing extensions. As here shown, this joint is made of flexible tape I², which may be of any suitable type and may or may not be painted or gummed. In any event it serves to make an air tight joint a manual control which includes the link J

55 which is pivotally connected to the slide at one end and pivotally connected to the end J' of a lever arm J² at its other end. This arm is pivoted as at J² and provided with a controlling handle J¹.

10 The use and operation of my invention are as follows:

The bag or other package to be filled is positioned over the nozzle and is held against accidental displacement by the dog above described. The weight on the scale is set

at a predetermined point to control the weight of material to be discharged into the package. Material may be fed into the hopper at that time or it may be previously fed to the same.

With the parts in the position shown in Figure 1 and the impeller in operation, the feed nozzle is opened and material will be discharged into the bag or other package, which, as above pointed out, is supported on the cradle which in turn rests upon the scale beam. As material is discharged into the package the scale beam will gradually be depressed and, the nozzle moving with it, the perforation therethrough will gradually move out of register with the perforation in the bottom of the impeller casing, and thus the amount of material discharged will be gradually reduced. When the predetermined amount of material has been discharged into the bag its weight will be sufficient completely to depress the scale beam and thus completely to close the nozzle opening and to prevent further discharge. The apron about the nozzle assembly, which is also mounted on the moving frame, is provided in order to prevent the lateral discharge of material which may escape during this operation due to leakage, and other causes. When the scale beam has come to rest the controlling handle is operated and the slide is moved across the nozzle opening so as to positively close the same. The filled package is now removed from the scale frame and the scale returns to its former position, the nozzle opening moving again into register with the opening in the bottom of the impeller casing; but since the slide has been moved across this opening no discharge can take place. Another package is placed in position on the nozzle and the operator then positively opens the slide valve and permits discharge into the package through the nozzle, and the cycle of operation is repeated. As the bag is filled and the scale beam is correspondingly depressed the depending lip on the casting C' covers the rear or inner opening of the nozzle, and a flat face on the casting F' extending above the inner opening of the nozzle prevents leakage or discharge of material from the impeller casing into the air as the scale beam descends.

Claims:

1. In a bag filling mechanism, a material impeller mounted about a rotary shaft and comprising a central hub provided with a plurality of laterally extending arms each having a longitudinal groove, in combination with a plurality of blades each provided with a longitudinal corrugation adapted to lie within one of such grooves, and a single bolt passing through each corrugation into the arm and fixing the blade in position.
2. In a bag filling mechanism, a material

- impeller mounted about a rotary shaft and comprising a central hub provided with a plurality of laterally extending arms, each of said arms having a longitudinal groove, 5 in combination with a plurality of blades, each provided with a longitudinal corrugation adapted to lie within one of such grooves, and a single bolt passing through a longitudinal slot within the corrugation and 10 adjustably securing the blade to the arm.
3. In a bag filling mechanism, a material impeller mounted about a rotary shaft and comprising two semi-annular members forming a hub, each having an arm extending radially outward along the line of division and another arm at right angles to the first said arm, bolts securing the two members to each other and upon the shaft, there 15 being a longitudinal groove along one side of each arm and a blade having a corrugation lying in the groove and a bolt passing through each corrugation into the adjacent arm and fixing the blade in position.
4. In a material supply system, a rotary impeller and a casing therefor having a removable segment, means for adjustably securing said segment upon said casing, said means including an arm removably attached to the outside of said casing and provided with a set screw whereby said detachable 30 side may be vertically adjusted, and a removable lining within a part of said casing, said lining being held in position by the main holding means for such removable arm.

Signed at Chicago county of Cook and 35 State of Illinois, this 22nd day of May 1922.

ADELMER M. BATES.
